AUTOMATIC CUT-OFF DEVICES PARTICULARLY FOR ELECTRIC SMOOTHING IRONS

Ronald James Marriott, Toorak, and John Francis Coyne, Malvern, Australia, assignors to Hecla Electrics Proprietary Limited, South Yarra, Victoria, Australia, a company of Victoria

Application December 14, 1954, Serial No. 475,154

Claims priority, application Australia April 29, 1954

8 Claims. (Cl. 200—138)

This invention relates to thermostat control devices for electrical smoothing irons and various other electrical appliances having a heating element and more particularly concerns that type of device which is manually adjustable over a predetermined temperature range and incorporates a bimetallic or other heat sensitive element for effecting the desired opening and closing movements of an associated switch.

Known thermostat control devices of the type mentioned, have proved to be satisfactory for existing types of smoothing irons, but are not sufficiently sensitive to meet the requirements, for example, of a novel type of pressing iron which forms the subject of our copending United States patent application and which functions to rapidly distribute steam, from the damp fabric, that is normally trapped beneath the iron.

The primary object of the present invention is to provide an improved device of the kind indicated, which is more sensitive than hitherto and capable of relatively fine temperature adjustment in accordance with requirements.

Another object is to provide an improved thermostat control device in the form of a unit which is preset to the desired temperature range at the factory and is capable of being quickly and easily fitted to and removed from an iron when required without having to change the setting.

Other objects and various novel constructional features of the invention will be more readily apparent from the following more detailed description which for convenience, relates to the application of the improved thermostat control device to an electric iron.

Referring to the drawings which form part of this specification:

Figure 1 is a longitudinal section showing the improved thermostat control device fitted to an electric iron.

Figure 2 is a plan view of some of the parts seen in Figure 1.

Figure 3 is a cross section taken on the line III—III of Figure 1, parts being omitted for convenience of illustration.

Figure 4 is a fragmentary sectional plan view of some of the parts seen in Figure 2.

Figure 5 is a longitudinal section on an enlarged scale, showing a bimetallic strip and associated wedge which form part of the improved device.

Electrical smoothing irons of the type to which this invention is particularly applicable, include an iron sole 2 and a clamping plate 3 between which an electrical heating element 4 is held fast. The latter may consist of a ribbon like metal winding arranged in the form of a sandwich between sheets of mica or other insulating material. A series of anchoring bolts 6 upstanding from the iron sole may be employed for connecting the assembly together and also for holding a cover plate (not shown) in the desired operative position.

In accordance with the present invention, the im-

2

proved thermostat control device includes a heat conducting base plate 7 preferably in the form of a relatively thin metal stamping of substantially the same or part of the same shape and size as that of the clamping plate.

- 5 This base plate, which carries an electrical switch and parts associated therewith, is adapted to be located between the iron sole and the heating element so as to constitute a relatively large heat conducting surface for influencing a thermostat element associated with the switch.
- 10 The latter consists of fixed and movable contacts 8 and 9 preferably of silver to minimize pitting and which are carried by a fixed leaf and a resilient leaf 11 and 12 respectively.

In order to avoid or minimize direct heating of these leaves they are spaced from and thermally insulated from the base plate for example, upon a plurality of upstanding posts 13 attached to the base plate. These posts may be located near the rear end of the base plate, and be connected to the fixed and movable leaves near 20 the rear end of the latter so that the leaves may extend lengthwise of the base plate in overlying relationship.

The fixed leaf 11 is relatively stiff and for that purpose may be of substantially channel shape in cross section as seen more clearly in Figure 3. The movable leaf 12 is electrically insulated from the fixed leaf and is composed of spring like metal. The fixed and movable contacts are carried by their respective leaves near the front ends thereof whilst the rear ends of the leaves are adapted to be electrically connected in any suitable manner with 30 contact pins or the like on the iron.

The aforesaid thermostat element preferably consists of a bimetallic strip 14 which may also extend lengthwise of the base plate beneath the forward end portion of the fixed and movable leaves. The bimetallic strip may be 35 located in an air gap above an aperture 16 in the base plate with one end of the bimetallic strip thermally connected to a bridge 17 over the gap and which forms part of the base plate.

Associated with the foregoing are manually adjustable 40 temperature control means including adjustable thrust transmission means for transmitting movement of the bimetallic strip 14 to the movable contact 9. Such thrust transmission means include a longitudinally adjustable wedge 18 which is loosely connected to the free end of the bimetallic strip. For this purpose, the latter may be provided with laterally spaced and opposed claws 19 adapted to slidably engage longitudinal flanges on the opposite sides of the wedge. A cross rib 21 of convex cross section may extend between the opposed 50 claws so as to contact the bottom of the wedge and thus provide a desirable line or substantially knife edge engagement between these parts.

Any suitable means are employed for effecting lengthwise movement of the wedge. For example, such means 55 may consist of an upstanding oscillatable spindle 22 carried by the mounting means for the aforesaid leaves and which is connected to the rear end of the wedge by pivoted linkage 23. A limit stop 24 is preferably provided for restricting turning movement of the spindle 60 which is also preferably spring influenced to oppose undesirable rotation.

The spindle 22 is fitted at its upper end with a pointer 65 associated with a fixed scale, for example, on the iron cover so as to indicate the temperature at which the iron is to operate. Tongue and groove connections are preferably employed for connecting the pointer to the spindle so that the pointer may be removed and replaced when required without disturbing the correct operative relationship between the pointer and its fixed scale.

Mounted upon the movable leaf 12 near the free end thereof, is a depending thrust pin 27 which is located in

registry with the top inclined face of the wedge. The effective length of this thrust pin is adjustable and for this purpose the movable leaf may be fitted with a screwed bush which is electrically insulated from the leaf and adapted to carry the thrust pin. The latter is screwed lengthwise and may be provided at its upper end with a slot for turning purposes and also with a lock nut 29. The fixed leaf 11 is provided with a hole 31 in substantial axial alignment with the thrust pin so that the latter may pass freely therethrough and be engaged by the wedge.

It will be appreciated from the foregoing, that the base plate, switch and manually adjustable thermostat control devices, may be formed as a unitary assembly with the operative position of the thrust pin preferably preset at the factory. Such a unit may obviously be readily fitted to and removed from an iron when required.

In use, the effective area of the base plate 7 and its operative position in relation to the heating element 4 and the iron sole 2 enables it to rapidly transfer heat from almost the entire area of the iron sole and also the heating element to the bimetallic strip 14. Upon heating, the free end of the latter warps upwardly and brings the upper edge of the wedge 18 carried thereby into engagement with the lower end of the thrust pin 27 for opening the contacts. Slight cooling of the base plate enables the contacts to close and thus resume heating of the iron sole for the purpose of maintaining it at the desired constant temperature. This temperature is easily determined by the user simply by turning the pointer 26 to the required marking on the fixed scale.

It will be apparent from the foregoing, that the transfer of heat by conduction and radiation to the bimetallic strip both from the iron sole as well as from the heating element is far more efficient than hitherto, whilst the adjustable wedge and screwed thrust pin renders the device particularly sensitive.

Although the invention has been described with particular reference to its application to an electrical smoothing iron, it will be understood that its use is not limited thereto as obviously the improved thermostat control device may be readily fitted, for example, to hot plates and a variety of other electrical heating appliances.

Various other alterations, modifications and/or additions may be introduced into the foregoing construction and arrangement of parts without departing from the ambit of the invention as defined by the appended claims.

Having now described our invention, what we claim as new and desire to secure by Letters Patent is:

1. An improved thermostat control device of the kind indicated for use with electrical smoothing irons and other electrical appliances having a heating element, comprising an electrical switch mounted on said iron or other appliance and wired in circuit with said heating element, a heat sensitive element fixedly mounted in relation to said switch in such a manner that part of said heat sensitive element is movable in relation to the contacts of said switch and manually adjustable temperature control means located between said heat sensitive element and said contacts whereby movement of said heat sensitive element in response to temperature changes in said smoothing iron or other appliance is adapted to effect relative movement between said contacts.

2. An improved thermostat control device of the kind indicated for use with electrical smoothing irons and other electrical appliances having a heating element, comprising a heat conducting base plate mounted between the heating element and part of the iron or other appliance to be heated, an electrical switch wired in circuit with said heating element and which is fixedly mounted on said base plate and has relatively movable contacts one of which is spring influenced so as normally to maintain said contacts closed, a heat sensitive element also fixedly mounted on said base plate in such a manner that part of said element is movable towards and away from

said spring influenced contact to open and close said contacts and manually adjustable temperature control means including adjustable thrust transmission means located between said spring influenced contact and the movable portion of said heat sensitive element so as to vary the degree of movement of said heat sensitive element that is required to open said contacts.

3. In an improved thermostat control device for use with electrical smoothing irons and other electrical appliances having a part to be heated and a heating element for heating said part, the improvement comprising an electrical switch mounted on said appliance and wired in circuit with said heating element, a heat sensitive element fixedly mounted in relation to said switch in such a manner that part of said heat sensitive element is movable in relation to the contacts of said switch, and manually adjustable temperature control means located between said heat sensitive element and said contacts whereby movement of said sensitive element in response to temperature changes in said part to be heated is adapted to effect relative movement between said contacts, said manually adjustable temperature control means including a longitudinally slideable wedge loosely mounted upon the movable portion of said heat sensitive element, a cooperating thrust member carried by one of said contacts and located in registry with the inclined face of said wedge, and means for moving said wedge lengthwise so as to vary the degree of movement of said heat sensitive element that is required to open said contacts.

4. In an improved thermostat control device for use with electrical smoothing irons and other electrical appliances having a part to be heated and a heating element for heating said part, the improvement comprising an electrical switch mounted on said appliance and wired in circuit with said heating element, a heat sensitive element fixedly mounted in relation to said switch in such a manner that part of said heat sensitive element is movable in relation to the contacts of said switch, and manually adjustable temperature control means located between said heat sensitive element and said contacts whereby movement of said sensitive element in response to temperature changes in said part to be heated is adapted to effect relative movement between said contacts, said manually adjustable temperature control means including a longitudinally slideable wedge loosely mounted upon the movable portion of said heat sensitive element, a cooperating thrust member carried by one of said contacts and located in registry with the inclined face of said wedge, and means for moving said wedge lengthwise so as to vary the degree of movement of said heat sensitive element that is required to open said contacts.

5. In an improved thermostat control device for use with electrical smoothing irons and other electrical appliances having a part to be heated and a heating element for heating said part, the improvement comprising an electrical switch mounted on said appliance and wired in circuit with said heating element, a heat sensitive element fixedly mounted in relation to said switch in such a manner that part of said heat sensitive element is movable in relation to the contacts of said switch, and manually adjustable temperature control means located between said heat sensitive element and said contacts whereby movement of said sensitive element in response to temperature changes in said part to be heated is adapted to effect relative movement between said contacts, said manually adjustable temperature control means including a longitudinally slideable wedge loosely mounted upon the movable portion of said heat sensitive element,

a cooperating thrust member carried by one of said contacts and located in registry with the inclined face of said wedge, and means for moving said wedge lengthwise so as to vary the degree of movement of said heat sensitive element that is required to open said contacts, in combination with an oscillatable spindle carried by said base plate and connected by pivoted linkage with said wedge, said spindle having an associated limit stop for restricting its movement and a pointer for providing a visible indication of such movement.

6. In an improved thermostat control device for use with electrical smoothing irons and other electrical appliances having a part to be heated and a heating element for heating said part, the improvement comprising an electrical switch mounted on said appliance and wired in circuit with said heating element, a heat sensitive element fixedly mounted in relation to said switch in such a manner that part of said heat sensitive element is movable in relation to the contacts of said switch, and manually adjustable temperature control means located between said heat sensitive element and said contacts whereby movement of said sensitive element in response to temperature changes in said part to be heated is adapted to effect relative movement between said contacts, said manually adjustable temperature control means including a longitudinally slidable wedge loosely mounted upon the movable portion of said heat sensitive element, a cooperating thrust member carried by one of said contacts and located in registry with the inclined face of said wedge, and means for moving said wedge lengthwise so as to vary the degree of movement of said heat sensitive element that is required to open said contacts, which are arranged in overlying relationship above said heat sensitive element and the wedge carried thereby, said contacts being carried by leaves, one of which is fixed whilst the other is resilient so that its contact may be moved towards and away from its associated fixed contact, the spring influenced contact being provided with said thrust member the outer end of which is located adjacent to the inclined face of said wedge and means for adjusting the effective length of said thrust member.

7. An electrical smoothing iron or other appliance having a part to be heated, an electrical heating element and a thermostat control device wired in circuit with said heating element, said thermostat control device comprising

5

ing a heat conducting base plate located between said heating element and said part to be heated, an electrical switch fixedly mounted on said base plate and having a pair of relatively movable contacts carried by overlying leaves, one of which is fixed whilst the other is resilient, a heat sensitive element in the form of a bi-metallic strip one end of which is thermally fixed to a bridge over an air gap in said base plate whilst the other end is free to flex towards and away from said movable contact, the

10 resilient leaf of which carries a depending thrust pin which is screw threaded so that its effective length may be varied, a longitudinally slidable wedge resting upon a cross rib on the free end portion of said bi-metallic strip and having a pair of laterally spaced and opposed claws adapted to loosely accommodate therebetween longitudinal flanges on the sides of said wedge which is connected by pivoted linkage to an oscillatable spindle also carried by said base plate and provided with a limit stop and a pointer.

8. For use in an electric smoothing iron or other electrical appliance having a part to be heated, a thermostat control device in the form of a unit and comprising a heat conducting base plate having mounting means for an electric switch consisting of fixed and movable contacts carried by overlying leaves, one of which is fixed whilst the other is resilient, a heat sensitive element in the form of a bi-metallic strip thermally connected near one end to a bridge over an air gap in said base plate so that the free end portion of said strip is located between said

25 leaves and the base plate, a longitudinally slidable wedge loosely connected to the outer end portion of said bi-metallic strip so as to be located in registry with the free end of a longitudinally adjustable thrust pin carried by said resilient leaf and manually adjustable means for 30 effecting lengthwise movement of said wedge.
